UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING-MACHINE.

1,345,894.

Specification of Letters Patent.

Patented July 6, 1920.

Application filed August 1, 1919. Serial No. 314,679.

To all whom it may concern:

Be it known that I, GEORGE A. SEIB, citizen of the United States, and resident of Ilion, in the county of Herkimer and State 5 of New York, have invented certain new and useful Improvements in Typewriting-Machines, of which the following is a specification.

My invention relates to typewriting machines and more particularly to the line lock mechanism for such machines.

The objects of my invention, generally stated, are to provide an improved line lock mechanism which is not liable to be damaged or broken and which is effective in operation.

To the above and other ends which will hereinafter appear my invention consists of the features of construction, arrangements of parts and combinations of devices set forth in the following description and particularly pointed out in the appended claims.

In the drawings, wherein like reference 25 characters indicate corresponding parts in the different views,

Figure 1 is an enlarged detail fragmentary front elevation with parts in section showing a portion of a line lock mechanism 30 and some of the associated parts.

Fig. 2 is an enlarged detail fragmentary bottom plan view of the same.

Fig. 3 is a detail transverse sectional view of the parts taken on the line $\text{--} \text{--}$ of Fig. 1 35 and looking in the direction of the arrow at said line.

Fig. 4 is an enlarged detail fragmentary skeletonized perspective view of the line lock mechanism and some of the associated 40 parts.

The present invention is in the nature of an improvement on the construction employed in the Nos. 10 and 11 Remington machines, and on that disclosed in the patent 45 to Berry No. 956,672, dated May 3, 1910.

So far as the present invention is concerned it may be understood to be embodied in a No. 10 or No. 11 Remington machine, though it may be embodied in other styles 50 of machines.

The key levers 1 are each provided with an upwardly extending hook-like projection

2, beneath the engaging face 3 of which a locking flange 4, on a line locking member or bar 5, is adapted to be shifted to limit or prevent a depression of each key lever, and thereby prevent a printing operation and an actuation of the carriage escapement as in the Remington machines.

The locking bar 5 is pivoted at 6 to the 60 base of the machine and has a forwardly extending arm 7 to which the lower end of a depending two-part link 8 is pivoted. The upper end of the link is pivoted at 9 to an angular sheet metal lever 10, fulcrumed at 65 11 to a post 12 on the top plate 13 of the machine. The lever 10 is bifurcated at 14 to receive a depending finger or flange 15 of a sheet metal slide, designated as a whole by the reference numeral 16. This slide is 70 mounted for longitudinal sliding movement on a fixed support, which in the present instance is the forward fixed carriage rail 17 secured by screws 18 to the post 12, and to a corresponding post at the other side of the 75 top plate. The slide is slotted at 19 to receive the stems of shouldered, headed, screws 20, the threaded stem of each of which is received in a tapped opening in the under side of the rail 17. The rail has 80 a longitudinal groove or cavity 21 cut in the under side thereof, thus forming a housing in which parts of the line lock mechanism are received, as will presently appear. It will be seen that the slide 16 covers the 85 bottom or open mouth of the cavity so that it is inclosed on all sides. A lug 22 is struck up from the body of the slide and extends into the cavity or housing. A contractile 90 spring 23 is contained within the cavity or housing, being connected at one end to the lug 22 and at its opposite end to a pin 24 seated at one end in an opening 25 in the rail and projecting into the cavity 21 therein. The force of the spring is exerted to 95 move the slide 16 to the right until the left-hand end walls of the slots 19 contact with the screws 20.

A sheet metal link or connecting member, designated as a whole by the reference numeral 26, is pivoted on the slide by a shouldered, headed, pivot pin 27 riveted to the slide. The left-hand end of the member 26 has an upwardly bent stop or finger 28 which

extends up into an opening or slot 29 in the slide, and coacts with an end wall 30 thereof to limit the pivotal movement of the member 26 in one direction, or back to normal position. A lug 31 is struck up from the member 26 and projects upwardly through an opening or slot 32 in the slide and into the cavity 21. A contractile returning spring 33 is contained in the cavity or housing, and is connected at one end to a lug 31, and at its opposite end to a lug 34 struck up from the slide and extending into the cavity or housing. The force of this spring is exerted normally to maintain the connecting member 26 in the position shown in Fig. 2, with the stop 37 bearing against the rear wall 30 of the slot in which it is received. To the right of its pivot the member 26 is formed with a goose-neck or extension which terminates in a bifurcated or slotted portion 35 that embraces an extension 36 of a line lock actuator and stop, designated as a whole by the reference numeral 37. This stop is mounted on a casting 38 secured to the front rail 17 by screws 39. Cylindrical bearings are formed in the casting 38 to receive trunnions 40 and 41 on the stop 37 and by which the stop is mounted for sliding and pivotal movement. From an inspection of Fig. 3 it will be seen that a portion 42 on the stop extends into a slot or cut-out 43 in the carriage rail 17 and that the right-hand face of the part 42 contacts with the right-hand wall 44 of the cut-out, whereas the left-hand face of the part 42 is adapted to coact with the left-hand wall 45 of the cut-out, and thus limit the sliding movement of the line lock stop in opposite directions. However, the stop may be turned on its trunnions with the aid of a finger piece 46 without displacing the part 42 from the cut-out in the rail. This pivotal movement of the line lock stop is provided in order to clear the usual carriage-carried line lock stop 47 and thereby enable the operator to release the line lock as in the usual Remington construction. It will be understood that when the line lock stop 37 receives a pivotal movement, or is rocked to release as just described, the connection between the stop and the member 26 will cause the latter to turn around its pivot 27 on the slide against the force of the spring 33, and without breaking the connection between the stop 37 and the slide which enables the two to move together in their sliding movements. When the stop 37 is released by the removal of the finger pressure of the operator, the spring 33 exerts its force to turn the connecting member 26 back to normal position, and through said member to rock the stop 37 back to normal position.

As the carriage moves from right to left, the adjustable carriage-carried line lock stop 47 coacts with an extension or contact lug 37a on the stop 37, and carries the latter

along with the carriage. This motion of the stop 37 is transmitted through the connecting device 26 to the slide 16, moving the latter against the power of its spring 23, thereby rocking the lever 10 and moving the locking bar to locking position. When the carriage is returned to the right, the spring 23 returns the slide 16 to the right, carrying the stop 37 back with the slide. At this time the spring 33 moves bodily with the slide, and does not enter into action except to hold the member 26 fixed relatively to the slide, and to hold the stop 37 against turning movement.

From the foregoing description it will be seen that the construction of the parts is such that they may be easily assembled; that the springs for returning the parts are housed and maintained protected from damage, or from being broken in handling the machine, and that the construction is strong and efficient in use, and is not liable to stick and result in an ineffective or faulty operation.

What I claim as new and desire to secure by Letters Patent, is:

1. In line lock mechanism for typewriting machines, the combination of a carriage actuated slide for controlling the locking means, a spring connected directly to said slide for returning it to normal position, and a carriage rail on which said slide is mounted for sliding movement, said rail having a cavity in which said spring is contained.

2. In line lock mechanism for typewriting machines, the combination of a slide for controlling the locking means, a line lock stop, a member pivoted to said slide and operatively connected to said line lock stop, a returning spring for said connecting member, and a carriage rail on which said slide is mounted, said rail having a cavity in which said spring is contained.

3. In line lock mechanism for typewriting machines, the combination of a line lock stop, a slide for controlling the locking means, a connecting member intermediate said slide and stop and pivoted on the slide, a spring for returning the slide, a second spring for returning the connecting member in its pivotal movement, and a carriage rail on which said slide is mounted, said rail having a cavity in which both of said springs are contained.

4. In line lock mechanism for typewriting machines, the combination of a carriage rail having a cavity in the under side thereof, a carriage actuated slide mounted on said rail and serving as a cover for said cavity, a line locking member controlled by said slide, and a returning spring for the slide contained in said cavity.

5. In line lock mechanism for typewriting machines, the combination of a fixed

supporting member having a cavity therein, a slide mounted on said member and serving as a cover for said cavity, a line locking member controlled by said slide, a returning spring for the slide contained in said cavity, a line lock stop, a connecting member intermediate said stop and slide and mounted on the latter for independent pivotal movement, and a second spring contained in 10 said cavity and connected to said connecting member for returning it in its independent movement.

6. In line lock mechanism for typewriting machines, the combination of a line locking member, a slide for controlling said locking member, a spring for returning said slide, a line lock stop, a connecting member intermediate said stop and slide and pivoted to the latter for independent movement 15 thereon, and a separate spring for returning the connecting member in its pivotal movement on the slide.

7. In line lock mechanism for typewriting machines, the combination of a line locking member, a slide for controlling said locking member, a spring for returning said slide, a line lock stop, a connecting member intermediate said stop and slide and pivoted to the latter, a separate spring for returning 20 the connecting member in its pivotal movement on the slide, and a support on which said slide is mounted, said support having a cavity in which both said springs are contained.

25 8. In line lock mechanism for typewriting machines, the combination of a line lock stop mounted for pivotal and for sliding movements, a slide, a line locking member controlled by said slide, and a connecting member pivoted on said slide and having a slotted portion that embraces a part of 40 said stop and causes the stop and slide to have a sliding movement together and enables the connecting member to receive a pivotal movement on the slide when the stop receives a pivotal movement.

50 9. In line lock mechanism for typewriting machines, the combination of a line lock stop mounted for pivotal and for sliding movements, a slide, a line locking member controlled by said slide, a connecting member pivoted on said slide and having a slotted portion that embraces a part of said stop and causes the stop and slide to have a 55 sliding movement together and enables the connecting member to receive a pivotal movement on the slide when the stop receives a pivotal movement, a spring connected to said slide for returning it to normal position, and a second spring connected at one end to the slide and at the other end to said connecting member for returning it and the stop to normal positions in their pivotal movements.

65 10. In line lock mechanism for typewrit-

ing machines, the combination of a line lock stop mounted for pivotal and for sliding movements, a slide, a locking member controlled by said slide, a connecting member pivoted on said slide and having a slotted portion that embraces a part of said stop and causes the stop and slide to have a sliding movement together and enables the connecting member to receive a pivotal movement on the slide when the stop receives a pivotal movement, a spring connected to said slide for returning it to normal position, a second spring connected at one end to the slide and at the other end to said connecting member for returning it and the stop to normal positions in their pivotal movements, and a grooved support containing both of said springs.

11. In line lock mechanism for typewriting machines, the combination of a line lock stop, a line locking member, an intermediate sheet metal slide formed with a lug struck up therefrom, a support for said slide, said support having a housing in which said lug is received, and a spring contained in said housing and connected at one end to said lug and at the other end to a pin in the housing.

12. In line lock mechanism for typewriting machines, the combination of a line lock stop, a line locking member, an intermediate sheet metal slide formed with a lug struck up therefrom, a support for said slide, said support having a housing in which said lug is received, a sheet metal connecting member pivoted to said slide and connected with said stop, a lug struck up from said connecting member and entering said housing, and a spring contained in said housing and connected at one end to the lug on the slide 100 and at its other end to the lug on the connecting member.

13. In line lock mechanism for typewriting machines, the combination of a line lock stop, a line locking member, an intermediate sheet metal slide formed with a lug struck up therefrom, a support for said slide, said support having a housing in which said lug is received, a spring contained in said housing and connected at one end to said lug 115 and at the other end to a pin in the housing, a second lug struck up from said slide and entering said housing, a sheet metal connecting member pivoted on said slide and operatively connected to said stop, said connecting member having a lug struck up therefrom and entering said housing, and a second spring contained in said housing and connected at one end to the lug on the connecting member and at the other end to the 120 second lug on the slide.

14. In line lock mechanism for typewriting machines, the combination of a line lock stop mounted for pivotal and sliding movement, a carriage rail having a housing, a 130

slide mounted on said rail and covering the mouth of said housing, a connecting member pivoted on said slide and operatively connected to said stop, a locking member controlled by said slide, and returning means for the slide and connecting member contained in said housing.

Signed at Ilion, in the county of Herkimer and State of New York, this 29th day of July, A. D. 1919.

GEORGE A. SEIB.
